UNITED STATES PATENT OFFICE.

FRANK HOW LANGMUIR, OF NEWARK, NEW JERSEY, ASSIGNOR TO NEVERBREAK TRUNK COMPANY, A CORPORATION OF NEW JERSEY.

LUGGAGE.

Application filed June 11, 1927. Serial No. 198,078.

This invention relates to luggage, and for purposes of being definite as to one specific construction is shown as embodied in a wardrobe trunk, but it is to be understood that the invention is not confined to use in wardrobe trunks only, as it is equally applicable to other luggage, such as traveling cases.

The objects of the invention are to provide a structure by which the wardrobe space or compartment may be of reduced size and the trunk or traveling case correspondingly small and compact; to fold the skirts or lower parts of long coats and the like so as to shorten the space required for the garment and also render the folded portion substantially the thickness of the upper part or shoulders; to thus enable the garments to be more evenly packed, with less looseness and likelihood of displacement and crumpling in transit; to automatically fold the skirts or lower parts of the garments into place; to secure simplicity of construction and operation, and to obtain other advantages and results as may be brought out in the following description.

Referring to the accompanying drawings, in which like numerals of reference indicate similar parts throughout the several views,

Figure 1 is a perspective view of a wardrobe trunk to which my invention is applied;

Figure 2 is a vertical sectional view looking edgewise of the wardrobe compartment of the trunk, showing the way garments are first inserted therein;

Figure 3 is a front view thereof;

Figure 4 is a view corresponding to Fig. 2 illustrating with a single garment the position of parts when the trunk is packed, and

Figure 5 is a front view of the same.

In the specific embodiment of the invention illustrated in said drawings, the reference numerals 1, 2 indicate the two sections of a trunk of the wardrobe type, one section, as 1, having a compartment 3 therein for hanging garments on properly supported garment hangers 4, and the other section 2 having a tier of drawers 5 therein as is common and well-known in the art. Heretofore it has been sought to make the trunk or other luggage long enough to accommodate garments such as coats so that most of them would not more than reach the lower end of the trunk; no provision was made for such garments that were too long for the compartment, and they would get badly wrinkled in packing and

in transit. This not only tended toward manufacture and use of large and bulky luggage, but also proved unsatisfactory because since the garments have much less thickness at their lower portions than at their upper portions, due partly to the thickness of the hangers, space was wasted at the bottom of the wardrobe portion.

In carrying out the present invention, the compartment 3, wherein garments are to be hung, is made much shorter than the usual garments which are to be packed therein, and the skirts of the garments are folded and held smoothly in place approximately as thick as the shoulders. Heretofore a follower has been employed for holding the garments pressed against the back of the compartment, and in the present invention, such a follower is also used for the additional purpose of effecting a proper fold transversely of the garments. The particular follower shown herein consists of a transverse rod 6 of a length substantially the width of the trunk compartment and adapted to be hooked into appropriate socket members 7, 7 therefor at the sides of the compartment near the bottom and toward the rear thereof. Near each end of the rod is a spiral spring 8 connected to a bar 9 which in turn is mounted in the hem of a curtain 10, which is secured at its upper end a the top and rear of said compartment. When the trunk is packed, therefore, the curtain 10 may be drawn over the top of the hangers, downwardly in front of the garments and then by pushing downwardly and rearwardly upon the rod 6 the garments will be pushed back into place ready for folding and the ends of the rod are then hooked into place in socket members 7, 7 with springs 8, 8 under tension. Any other form of follower providing a cross-member near the bottom of the compartment around which the garments can be folded upward may be employed, however.

As an essential part of the present invention, a folder 11 is provided for enabling the skirts of the garment which extend beyond said cross-rod 6 to be folded into place. This folder 11 is herein shown as a substantially U-shaped structure composed of a single length of stock such as heavy wire or rod, providing a middle portion 12 of a length approximately the width of the compartment and side portions 13 which are preferably parallel and of equal length. In manufacture, the length of

said side portions 13 is made to equal the length desired for the folded lower ends of the garments, and the extremities of said side portions 13 are suitably pivoted to the trunk 5 section, as by being bent in the present showing to provide trunnions for insertion in fixed ears 14. These ears are shown formed by the upturned ends of a bar 15 secured to the bottom 10 of the compartment, said bar being preferably back from the front edge of the compartment so when the bail is swung down the front edge of the compartment forms a ledge to support it, but obviously the bail could be pivotally mounted in any suitable 15 way. Any other form of a folder to produce the desired fold in the garments could be employed, also.

Preferably, a curtain 17 is mounted at one end on the middle portion 12 of the bail 11, 20 and is secured at its other end, as by fasteners 18, Fig. 1, to the bottom of the compartment, and when the bail is turned up this curtain acts to smoothly fold up, and hold the ends 25 of the garments with their extremities hanging downwardly in front, as shown in Figs. 4 and 5. Spring detents 19 may be provided on the side walls of the compartment to engage the side portions 13 of the bail when said bail is swung up, and preferably these detents 30 19 are adapted to hold the bail in any one of a series of positions according to the number of garments in the compartment.

Because of the saving in length of the compartment 3 for the garments, by use of my 35 invention in an ordinary trunk, it is practical to provide a drawer 20 in the bottom of the trunk section. It is, however, not necessary to provide this drawer, as the article of lug-

gage may be shortened, if preferred, by that much more, and indeed, for a hand case or 40 automobile case, the drawer would be omitted. It will be observed, however, in the present showing, that use of the drawer raises the garments draped over the front of the bail 11, in packing, from lying on the floor and is 45 therefore a desirable part of the structure.

Various detail modifications may be made in manufacturing luggage embodying my invention, by those skilled in the art, without departing from the spirit and scope of the invention, and I do not wish to be understood as limiting myself except as required by the following claims when construed in the light of the prior art.

Having thus described the invention, what I claim is:

1. In an article of luggage having a compartment for hanging garments therein, a follower adjacent the bottom of said compartment around which garments may be folded, 60 and a folder comprising a cross-bar lying beneath the lower forward parts of the garments as they are inserted and capable of being elevated rearwardly to fold said garments around said follower. 65

2. In an article of luggage having a compartment for hanging garments therein, a follower around which said garments may be folded, a folder, means for pivotally mounting said folder in the lower part of said compartment, said folder having a portion spaced from said pivotal mounting to swing against and with said garments for folding them around said follower. 70

FRANK H. LANGMUIR.
